UNITED STATES PATENT OFFICE.

JAMES P. LOCKE, OF TOLEDO, OHIO.

FLUSHING-TANK FOR WATER-CLOSETS.

SPECIFICATION forming part of Letters Patent No. 565,997, dated August 18, 1896.

Application filed October 7, 1895. Serial No. 584,829. (No model.)

To all whom it may concern:

Be it known that I, JAMES P. LOCKE, a citizen of the United States, residing at Toledo, Lucas county, Ohio, have invented certain new and useful Improvements in Flushing-Tanks for Water-Closets, of which the following is a specification.

In most of the flushing-tanks now in use a noise is produced in the operation of flushing, owing to the slow closing of the valve controlling the water-inlet to the tank, the aperture gradually becoming so small that a long-continued loud hissing sound is produced, especially when the water supply is under high pressure.

My invention relates to and its object is to provide means for overcoming this objection, and, more particularly, to provide large valve area for the inlet to the tank and mechanism whereby the inlet-valves may be easily and readily operated, and by which they will be closed positively, quickly, and noiselessly when the water reaches a given height within the tank after each flushing operation.

The further object of my invention is to accomplish the above result by means of mechanism which shall be cheap, durable, and positive in its operation, and which dispenses with the use of the supplemental floats heretofore employed to accomplish this object.

In the accompanying drawings, made part hereof, Figure 1 represents a central vertical longitudinal sectional elevation of my device; Fig. 2, an enlarged front view of the detents and their tripping mechanism, hereinafter referred to; and Fig. 3, a side view of the same.

Like letters of reference indicate like parts throughout the several views.

In the drawings, *a* is the tank, *b* the inlet-pipe, and *c* the outlet-pipe. The inlet and the siphon *c'*, leading to the outlet-pipe, are controlled by the usual lever *d* and pull-chain *e*. Above and partly within the tank is a chamber *f*, in which terminates the inlet-pipe *b*. In the lower part of this chamber are seated two valves *g* and *h*, having their downwardly-projecting stems connected with valve-lever *i*, which in turn is connected by chain *k* with the lever *d*. The lower part of the stems of the valves *g* *h* are forked, as at *g' h'*, the forks being astride of the lever *i*

and the contact part of the fork *g'* being normally nearer to the lever *i* than is the corresponding part of the fork *h'*, so that when the lever is raised by a pull on the chain *e*, through lever *d* and chain *k*, the valve-stem of valve *g* is first engaged, so that this valve is first opened, and the valve-stem *h'* is next engaged and the valve *h* opened, the arrangement being such that the valve *g* is always opened first and closed last. The valve *g* is of smaller area than the valve *h*, the smaller valve being designed to break the pressure in chamber *f*, so that the larger valve *h* may be readily lifted without requiring too much force and without too much strain upon the levers and chains.

Secured within the tank is a plate *l*, having one of its flat sides (hereinafter termed the "front side") parallel with and near to the lever *i*, the opposite side of this plate (hereinafter termed the "rear side") being parallel with and near to the lever *m*, which carries at its free extremity float *n*. The plate *l* is slotted through from front to rear side, as at *l'*. Pivoted to the rear side of the plate near its upper end and swinging in slot *l'* is a detent *o*, having near its lower end a horizontal portion or shoulder *o'*, from which curves downwardly a finger *o''*. The lever *i* normally rests just below the curved finger *o''*, and when this lever is pulled upwardly it presses and rubs against the curved finger, forcing the detent *o* into the slot *l* until the lever passes to a point above the shoulder *o'*, when the detent falls into its original position with the shoulder underneath the lever, where the lever is supported and retained until the detent is released by the mechanism now to be explained.

Upon the front side of the plate *l* are guides *p*, in which slides vertically bar *q*, having at its lower end eye *q'*, through which passes float-lever *m*, and having pivoted at and suspended from its upper end, as at *q''*, detent *r*. Pivoted to and suspended from the plate *l*, by means of eyes *s*, is a tripping-piece *t*, formed, preferably, of heavy stout wire, as are the detents *o* and *r*. This tripping-piece is formed at its upper end with two loops *t'*, which engage the eyes *s* on the plate. The loops *t'* are united by horizontal portion *t''* and the two vertical portions *t'''*, which latter

portions are united near their lower ends by horizontal cross-pieces t^4 and t^5 . The upper cross-piece or horizontal part t^2 projects outwardly from the front of the plate, as shown in Fig. 3, and is engaged on its lower side by a shoulder-piece r' , secured to the lower end of detent r and at about a right angle thereto. The cross-piece or horizontal portion t^4 passes between plate l and the detent o , which is bent, as at o^3 , as shown in Fig. 3, to receive the cross-piece t^4 , which serves as a stop against the outward swing of the detent o , and actuates this detent, as hereinafter described. The lower cross-piece or horizontal portion t^5 is designed to come in contact with the detent r at its extreme lower end. To effect this contact, the shoulder-piece r' is provided with an angular downward extension r^2 , having a spring r^3 , secured thereto on the side next to the cross-piece t^5 , the position of the spring r^3 being regulated by means of set-screw r^4 , passing through the lower end of angular extension-piece r^2 and abutting against the spring.

Assuming that the tank is filled with water to the line x , Fig. 1, and that the parts above described are assembled as shown in the drawings, the operation of my device is as follows: The pull-chain e being drawn downwardly, siphon c is opened in the usual way and the water is rapidly discharged from the tank through the siphon. By the same motion of the pull-chain e and its lever d , chain k , with its attached lever, is lifted upwardly. This movement of the lever i first lifts the valve g , which, being of small area, rises with but little resistance, and the larger valve h is next engaged and lifted. This valve, the pressure in the chamber f being broken, also lifts with but little resistance. The water now pours through valves g and h into the tank, but not so rapidly, however, as the tank is emptied through the siphon. When the lever i is raised by the action of the chains e k and lever d , it comes in contact with the downwardly and inwardly curved finger-piece o^2 of detent o and pushes this detent inwardly, in its slotted aperture, until the lever reaches a point above the horizontal shoulder o' of the detent, when the shoulder falls into place under the lever, holding it, with its attached valves g and h , stationary in its elevated position for the time being. As the water-line x is lowered by the discharge of the water through the siphon, the float n , with its lever m , descends, drawing down with it the sliding bar q , to which is pivotally secured the detent r . The spring r^3 , attached to the inclined extension-piece r^2 , normally rests against the upper side of cross-piece t^4 of the tripping-piece t . As the detent r descends with the float n , the inclined spring r^3 , sliding upon the cross-piece t^2 , forces the lower end of the detent outwardly until the shoulder r' reaches a point below the cross-piece t^2 , when the shoulder falls by its gravity beneath the cross-piece t^2 ,

as shown in Fig. 3. It will be seen that the valve-lever i is now supported by detent o o' in elevated position, and that the float-lever m , with its connected detent r , engages the projecting arm $t' t^2$ of the tripping mechanism. The water having been discharged from the tank down to line y , Fig. 1, through the siphon in the usual way, the tank begins to refill through the valves g and h , the float gradually rising until it reaches the water-line x , Fig. 1, lifting with it, through its lever, the vertical bar q , with its detent r . As the shoulder r' pulls upwardly on arm $t' t^2$, the cross-piece t^4 pulls outwardly upon detent o , behind which cross-piece t^4 passes, until the shoulder o' is drawn entirely within its recess. At this point the adjustment of the spring r^3 is such that the lower cross-piece t^5 comes in contact with the spring, throwing the shoulder r' out of engagement with the cross-piece t^2 at the same instant that the valve-lever i is released from the detent o , the shoulder r' now being at a point above the cross-piece t^2 . The lever, being released, falls, closing the two valves h g in quick succession without shock, jar, hissing sound, or other objectionable noise. It is necessary that the adjustment of the springs r^3 and r^4 should be such that the disengagement of the detent r from the tripping-piece t shall be simultaneous with the release and fall of the valve-lever, for the reason that if the valve-lever should fall first the float would rise no higher and the detent o would be held in inoperative position, so that at the next operation of the flushing mechanism the valve-lever i would find no support from the detent o . If, on the other hand, detent r were released from the tripping-piece t before the fall of the valve-lever, the detent o would not be operated, the valves would be retained in open position, and the flow of the water would be continuous.

The advantage of the arrangement of the air-chamber f and its valves, as shown and described, is that the compressed air prevents undue concussion upon the sudden closing of the valves g h , while the two valves of large and small area closing in succession serve somewhat the same purpose, as a cock or spigot which is opened and closed gradually tending to prevent concussion. It will be seen, moreover, that the large area of valve-opening provided by the two valves allows the escape of water as the chamber is emptied without the hissing sound which my invention is designed to obviate.

Having fully described my invention, what I claim, and desire to secure by Letters Patent, is—

1. In a flushing-tank for water-closets, a detent adapted to engage the inlet-valve lever and to hold the same against movement during the rise of the water in the tank, a float in said tank and connections intermediate said detent and said float, in combination with means for simultaneously releasing said

detent from said lever and said float from said intermediate connections, substantially as and for the purpose specified.

2. In a flushing-tank for water-closets, a detent adapted to hold open the valved inlet to the tank during the rise of the water therein, a float in said tank, a second detent controlled by said float, and an intermediate tripping mechanism common to both said detents, adapted to release both said detents simultaneously, substantially as and for the purpose specified.

3. In a flushing-tank for water-closets, a detent adapted to engage the inlet-valve lever, a float in said tank, a second detent controlled by said float, a tripping mechanism intermediate said detents, and adapted to release them simultaneously, in combination with means for adjusting the point at which said 20 second detent shall be released from said intermediate tripping mechanism, substantially as and for the purpose specified.

4. A water-closet flushing apparatus, comprising a tank, a water-supply pipe leading thereto, a flushing-pipe leading therefrom provided with suitable means for permitting the water to escape through said flushing-pipe, an air-chamber connected with said supply-pipe, a plurality of outlet-valves in said chamber, means for opening and closing said valves in succession, a detent adapted to engage the inlet-valve lever and to hold the same against movement during the rise of the water in the tank, a float in the tank, connections intermediate said detent and said float and means for simultaneously releasing said detent from said lever, and said float from said intermediate connections, substantially as and for the purpose specified. 25 30 35
